TUBE BEADING TOOL

Lloyd A. Smith, Hatboro, Pa.

Application August 1, 1945, Serial No. 608,328

9 Claims. (Cl. 153—73)

(Granted under the act of March 3, 1883, as
amended April 30, 1928; 370 O. G. 757)

1

This invention relates to new and useful improvements in tools or devices for forming beads in tubing, and more particularly to tools or devices of the type operable to form a raised circumferential bead in the exterior surface of tubing.

One of the difficulties encountered in existing types of tools or devices for forming beads in tubing is that such tools or devices generally are relatively cumbersome and require the use of two or more persons to effectively perform a beading operation upon a tube. Also the cumbersome and rather bulky nature of existing beading tools or devices in most cases precludes the performance of a beading operation upon tubing already installed in place in apparatus or equipment with the result that before such tubing can be properly beaded it is necessary that it be first removed from the apparatus or equipment in which installed. Furthermore existing beading tools and devices for the most part are characterized by operating limitations which preclude the formation of beads in certain tube shapes such as for example, gooseneck bends, elbows and the like.

With this in mind, the principal object of the present invention is to provide a novel tool or device for forming beads in tubing which may be substantially universally employed by a single person to effectively form beads in tubing of different sizes and without limitation as to the particular length, shape or configuration of the tube.

Another object of the invention is to provide a novel tool or device of the character described for forming beads in tubing which device is of relatively simple, compact construction thereby making it possible to be used effectively to bead tubing installed or located in small, closely confined areas.

A further object of the invention is to provide a novel tool or device of the character set forth for forming beads in tubing which may be employed to effectively form beads in tubing that is already installed in apparatus and equipment without necessitating removal of such tubing therefrom.

A still further object of the invention is to provide a novel tool or device having the features and characteristics set forth which is comparatively inexpensive to manufacture, and highly efficient in operation and use.

These and other objects of the invention and the various features and details of the construction and operation thereof are hereinafter fully set forth with reference to the accompanying drawing, in which:

Fig. 1 is an elevational view of the beading tool or device embodying the present invention.

Fig. 2 is a sectional view taken on line 2—2, Fig. 1.

Fig. 3 is a sectional view taken on line 3—3, Fig. 2; and

2

Fig. 4 is an exploded view in perspective showing a beaded tube and the die members of the present tool employed in the formation of the bead therein.

Referring now to the drawing, a tool or device made according to the present invention which is operable to form a circumferentially raised bead in tubing comprises a tubular body member 1 having circumferentially about the external surface thereof a raised portion or band 2 the surface of which is knurled or otherwise roughened as indicated at 3 to provide a hand grip portion for holding the tool. Formed internally of the tubular body 1, circumferentially of the inner surface thereof, is an annular flange 4 which is predeterminedly positioned intermediate of and with respect to the opposite ends of the body 1.

Referring now particularly to Fig. 2 of the drawing, there is removably positioned within one end of the body member 1 a pair of complementary semi-circular die members 5 which cooperate with one another to provide therewithin a tubular socket to receive the end portion of a tube 6 to be beaded. The socket formed by the complementary die members 5 extends coaxially of the body member 1 and at the inner ends of said die members 5 there are provided inwardly extending flanges 7 against which the inner end 30 of the tube 6 is adapted to set or abut when inserted in the socket in the manner shown. The die members 5 are provided at their outer ends with radial flange portions 8 which overlie the end face of the body member 1 and the axial length of said die members is such that the inner end faces thereof seat against or abut the internal annular flange 4 of the body member 1. Each of the die members 5 is provided adjacent its inner end with a groove 9 of arcuate cross-section 40 shape formed circumferentially in the inner surface thereof and these grooves 9 are cooperatively arranged with respect to each other to provide a continuous circumferential channel internally of the die members 5 when positioned in complementary relation within the end of the body member 1.

As stated, the die members 5 are removably positioned within the end of the body member 1, and hence may be readily and easily withdrawn 50 and replaced or interchanged with other similar die members 5 constructed and arranged to provide tube receiving sockets of different diameters for receiving tubing of different diameters. Furthermore, as between different sets of complementary die members 5 the cross-sectional dimensions of the grooves 9 in the inner surfaces thereof may vary in accordance with the diameter of the tube receiving socket formed by a particular pair of die members.

60 Rotatably mounted within the other end of the

tubular body member 1, and in oppositely abutting relation with respect to the internal flange 4 thereof is an end portion of an actuating member 10 that is coaxially disposed with respect to the body member 1 and the tube receiving socket formed by the complementary die members 5. The other or outer end of the actuating member 10 extends axially outward beyond the end face of the body member 1 and has secured therein, adjacent its outer end a cross pin 11 which serves as a handle portion adapted to be grasped to effect rotation of the actuating member 10 with respect to the body member 1 and a tube 6 within the socket formed by the die members 5.

The inner end of the actuating member 10 is provided with a circumferential surface portion 12 which engages the inner wall surface of the body member 1. The actuating member 10 is provided with a portion 13 of reduced diameter to provide clearance between that surface portion of the actuating member 10 and the adjacent internal wall surface of the body 1 for the reception of a plurality of roller bearings 14 arranged circumferentially of the member 10 as shown. The actuating member 10 has a shoulder 15 which is disposed coplanar with the adjacent end face of the body member 1. The actuating member 10 is retained rotationally within the body member 1, by means of an annular ring or member 16 which is secured to the end face of the body member 1 and extends radially inward so as to outwardly overlie the surface or shoulder 15 of the actuating member 10. The annular ring or member 16 is secured to the end face of the body 1, for example, by screws or the like 17, and embraces the adjacent circumferential surface portion of the actuating member 10.

Extending lengthwise inwardly from the inner end face of the actuating member 10 is a recess 18 which has inserted therein one end portion of a spindle 19. The inserted end of the spindle 19 is pivotally mounted upon a cross-pin 20 mounted cross-wise adjacent the inner end of the recess 18 to provide for pivotal movement of the spindle 19 about an axis normal to the rotational axis of the actuating member 10, and the other or free end of the spindle 19 extends endwise beyond the recess 18 and into the tube receiving socket formed by the complementary semi-circular die members 5. Mounted upon the outer or free end of the spindle 19 for rotation coaxially thereof is a beading tool element 21 having circumferentially thereof a raised bead forming portion 22 of arcuate cross-section shape. The beading tool 21 may be retained upon the free end of the spindle 19 by means of a headed screw, bolt or the like 23. It will be observed by reference to Fig. 2 of the drawing that the length of the spindle 19 and the position of the beading tool element 21 thereon are such that the raised circumferential portion 22 of the latter is in registry with the continuous channel formed circumferentially in the internal surfaces of the complementary die members 5 by the grooves 9 therein.

In the enlarged bearing surface portion 12 at the inner end of the actuating member 10 there is threaded a member 24 which is adjustable in a radially inward and outward direction with respect to the member 10 and the body member 1, and arranged to engage the spindle 19 pivotally carried by the actuating member 10 for the purpose of fixedly positioning the spindle 19, for example, in the angular relation shown in Fig. 2 of the drawing, to engage the beading tool 21

thereon outwardly against the internal wall surface of a tube 6 inserted in the socket of the complementary die members 5 in the relation hereinbefore described and shown in the drawing.

The threaded member 24 preferably is of the headless type and may be provided inwardly of its outer end face with a hexagonal or other shape axial socket for the reception of a suitable wrench or device to rotate the member 24 in the desired direction to adjust the position thereof radially of the actuating member 10 and thereby adjust the position of the beading tool 21 with respect to the inner surface of a tube 6. For the insertion of such a wrench or tool into the socket of the member 24 there are provided through the body member 1 a plurality of openings 25 located at suitably spaced intervals circumferentially of the body member 1.

In operation and use of the beading tool of the present invention, a selected pair of die members 5, providing a tube receiving socket of desired diameter, are inserted endwise into the appropriate end of the tool body member 1 until the inner end faces of said die members 5 seat against or abut the internal flange 4 of the body member 1. The end portion of a tube 6 to be beaded is then inserted endwise into the socket formed by the selected die members 5 so that the inner end edge of the said tube 6 is seated against or abuts against the flanges 7 provided at the inner end of said die members 5. The actuating member 10 is then rotated, if necessary, so as to align adjustable member 24 thereof with one of the openings 25 in the body member 1. A suitable wrench or tool is then inserted through the opening 25 and into the end socket of the member 24 to rotate the latter and adjust the same radially inward to cause its inner end to engage the spindle 19 and pivot the same about the pin 20 and engage the bead forming portion 22 of the beading tool element 21 into engagement with the internal wall surfaces of the inserted tube 6, the said member 24 being adjusted radially inward to such an extent that the bead forming portion 22 of the beading tool 21 is urged against the internal wall surface of the inserted tube under substantial pressure.

With the tube inserted and the device prepared for a bead forming portion as just described, the hand grip portion 3 of the body member 1 may be grasped and held against rotation by one hand of the operator who may then use his other hand to grasp the projecting handle portion and cross-pin 11 of the actuating member to manually rotate said actuating member 10 relative to the body member 1 thereby rotationally actuating the spindle 19 to cause the bead forming portion 22 of the tool 21 to circumferentially traverse the internal surface of the tube 6 and displace the metal thereof outwardly into the circumferential channel formed by the grooves 9 in the selected die members 5 so that there is formed in the tube a circumferential bead 26 which conforms to the cross-sectional size and configuration of said channel and the bead forming portion 22 of the beading tool 21. Upon completion of the bead forming operation, the member 24 is withdrawn from engagement with the spindle 19 to thereby release the pressure urging the beading tool 21 into engagement with the internal wall surface of the inserted tube 6. The die members 5, together with the beaded tube 6, may then be withdrawn axially from the body member 1 after which the complementary die members 5 may be

separated and removed from the beaded tube 6 as shown in Fig. 3 of the drawing.

From the foregoing description, it will be apparent that the present invention provides a novel tool or device for forming beads in tubing which may be substantially universally employed by a single person to effectively form beads in tubing of different sizes without limitation as to the particular length, shape or configuration of the tubing. The invention also provides a novel tool or device for forming beads in tubing which is of relatively simplified and compact construction and therefore available for use in small, closely confined areas with the result that it may be employed to form beads in tubing already installed in apparatus or equipment without the necessity of first removing such tubing. Furthermore, the invention provides a novel tool having the features and characteristics set forth and which is comparatively inexpensive to manufacture and highly efficient in operation and use.

While a particular embodiment of the present invention is illustrated and described herein, it is not intended to limit the invention to such disclosure, and changes and modifications may be made therein and thereto within the scope of the claims.

The invention described herein may be manufactured and used by or for the Government of the United States of America for governmental purposes without the payment of any royalties thereon or therefor.

I claim:

1. A tube beading tool comprising a tubular body member, complementary die members removably positioned inwardly of one end of said body member and cooperating to define a socket therein disposed coaxially with respect to said body member to receive the end portion of a tube to be beaded; said die members each having a groove of arcuate cross-section shape in its inner surface cooperable to form a continuous circumferential channel in the wall of the socket defined thereby, an actuating member having a portion thereof mounted within the other end of the tubular body member and arranged for rotation coaxially with respect to said body member and tube receiving socket defined by said die members, a beading tool actuatable by rotation of said actuating member arranged for rolling engagement circumferentially about the inner wall surface of a tube positioned in said socket, and means to position and maintain the beading tool in an angular position and in engagement against the internal wall surface of a tube positioned in said socket.

2. A tube beading tool comprising a tubular body member, complementary die members removably positioned inwardly of one end of said body member and cooperating to define a socket therein disposed coaxially with respect to said body member to receive the end portion of a tube to be beaded, said die members each having a groove of arcuate cross-section shape in its inner surface cooperable to form a continuous circumferential channel in the wall of the socket defined thereby; an actuating member having a portion thereof mounted within the other end of the tubular body member and arranged for rotation coaxially with respect to said body member and tube receiving socket defined by said die members, a beading tool actuatable by rotation of said actuating member arranged for rolling engagement circumferentially about the inner wall surface of a tube positioned in said socket, means

to position and maintain the beading tool in an angular position and in engagement against the internal wall surface of a tube positioned in said socket, and means to rotate said actuating member relative to the body member and cause the beading tool to circumferentially traverse the internal surface of the tube and displace the metal thereof outwardly into the circumferential channel of said die members.

10 3. A tube beading tool comprising a tubular body member, complementary die members removably positioned inwardly of one end of said body member and cooperating to define a socket therein disposed coaxially with respect to said body member to receive the end portion of a tube to be beaded, said die members each having a groove of arcuate cross-section shape in its inner surface cooperable to form a continuous circumferential channel in the wall of the socket defined thereby, an actuating member having a portion thereof mounted within the other end of the tubular body member and arranged for rotation coaxially with respect to said body member and tube receiving socket defined by said die members, a spindle pivotally carried by said actuating member for movement about an axis normal to the rotational axis thereof, a beading tool element swingably carried by said spindle and arranged for rolling engagement circumferentially about the inner wall surface of a tube positioned in said socket, and means carried by said actuating member to position the spindle angularly and engage the beading tool element against the internal wall surface of a tube positioned in said socket.

4. A tube beading tool comprising a tubular body member, complementary die members removably positioned inwardly of one end of said body member and cooperating to define a socket therein disposed coaxially with respect to said body member to receive the end portion of a tube to be beaded, said die members each having a groove of arcuate cross-section shape in its inner surface cooperable to form a continuous circumferential channel in the wall of the socket defined thereby, an actuating member having a portion thereof mounted within the other end of the tubular body member and arranged for rotation coaxially with respect to said body member and tube receiving socket defined by said die members, a spindle pivotally carried by the actuating member for movement about an axis normal to the rotational axis of said actuating member and projecting into the tube receiving socket of said die members, a beading tool element rotatably carried by said spindle for rolling engagement circumferentially about the inner wall surface of a tube positioned in said socket in registry with the continuous channel thereof, means to position the spindle angularly and engage the beading tool element against the internal wall surface of a tube positioned in said socket, and means to rotate said actuating member relative to the body member and cause the beading tool element to circumferentially traverse the internal surface of the tube and displace the metal thereof outwardly into the circumferential channel of said die members to thereby form in the tube a circumferential bead conforming to the cross-sectional size and configuration of the said channel and tool element.

5. A tube beading tool comprising a tubular body member, complementary die members removably positioned inwardly of one end of said body member and cooperating to define a socket

therein disposed coaxially with respect to said body member to receive the end portion of a tube to be beaded, said die members each having a groove of arcuate cross-section shape in its inner surface cooperable to form a continuous circumferential channel in the wall of the socket defined thereby, an actuating member having a portion thereof mounted within the other end of the tubular body member and arranged for rotation coaxially with respect to said body member and the tube receiving socket defined by said die members, a recess extending axially inward from the inner end face of said actuating member, a spindle having one end thereof pivotally mounted within said recess for movement about an axis normal to the rotational axis of said actuating member and having its free end projecting endwise outwardly of the recess into the tube receiving socket of said die members, means to position said spindle angularly in said recess, a beading tool element rotatably carried by the free end of said spindle and arranged for rolling engagement circumferentially about the inner wall surface of a tube positioned in said socket in registry with the continuous channel thereof, and means to rotate said actuating member relative to the body member and cause the beading tool element to circumferentially traverse the internal surface of the tube and displace the metal thereof outwardly into the circumferential channel of said die members to thereby form in the tube a circumferential bead conforming to the cross-sectional size and configuration of the said channel and tool element.

6. A tube beading tool comprising a tubular body member having complementary die members removably positioned inwardly of one end of said body member and cooperating to define a socket therein disposed coaxially with respect to said body member to receive the end portion of a tube to be beaded, said die members each having a groove of arcuate cross-section shape in its inner surface cooperable to form a continuous circumferential channel in the wall of the socket defined thereby, an actuating member having a portion thereof mounted within the other end of the tubular body member and arranged for rotation coaxially with respect to said body member and the tube receiving socket defined by said die members, a recess extending axially inward from the inner end face of said actuating member, a spindle having one end thereof pivotally mounted within said recess for movement about an axis normal to the rotational axis of said actuating member and having its free end projecting endwise outwardly of the recess into the tube receiving socket of said die members, a beading tool element rotatably carried by the free end of said spindle and arranged for rolling engagement circumferentially about the inner wall surface of a tube positioned in said socket in registry with the continuous channel thereof, means carried by said actuating member operable to position the spindle in an angular position and engage the beading tool element against the internal wall surface of a tube positioned in said socket, and means to rotate said actuating member relative to the body member and cause the beading tool element to circumferentially traverse the internal surface of the tube and displace the metal thereof outwardly into the circumferential channel in said die members to thereby form in the tube a circumferential bead conforming to the cross-sec-

tional size and configuration of the said channel and tool element.

7. A tube beading tool comprising a tubular body member having an annular flange interiorly thereof intermediate its ends, complementary die members removably positioned inwardly of one end of said body member in abutting relation with said flange and cooperating to define a socket therein disposed coaxially with respect to said body member to receive the end portion of a tube to be headed, said die members each having a groove of arcuate cross-section shape in its inner surface cooperable to form a continuous circumferential channel in the wall of the socket defined thereby, an actuating member having a portion thereof mounted within the other end of the tubular body member in oppositely abutting relation with respect to the internal flange thereof and arranged for rotation coaxially with respect to said body member and tube receiving socket defined by said die members, a beading tool actuatable by rotation of said actuating member arranged for rolling engagement circumferentially about the inner wall surface of a tube positioned in said socket in registry with the continuous channel thereof, and means to rotate said actuating member relative to the body member and cause the beading tool to circumferentially traverse the internal surface of the tube and displace the metal thereof outwardly into the circumferential channel of said die members to thereby form in the tube a circumferential bead conforming to the cross-sectional size and configuration of the said channel and tool element.

8. A tube beading tool comprising a tubular body member having an annular flange interiorly thereof intermediate its ends, complementary die members removably positioned inwardly of one end of said body member in abutting relation with said flange and cooperating to define a socket therein disposed coaxially with respect to said body member to receive the end portion of a tube to be headed, said die members each having a groove of arcuate cross-section shape in its inner surface cooperable to form a continuous circumferential channel in the wall of the socket defined thereby, an actuating member having a portion thereof mounted within the other end of the tubular body member in oppositely abutting relation with respect to the internal flange thereof and arranged for rotation coaxially with respect to said body member and tube receiving socket defined by said die members, a beading tool actuatable by rotation of said actuating member arranged for rolling engagement circumferentially about the inner wall surface of a tube positioned in said socket in registry with the continuous channel thereof, means carried by said actuating member adjacent the inner end thereof operable to position and maintain the beading tool in engagement against the internal wall surface of a tube positioned in said socket, and means to rotate said actuating member relative to the body member and cause the beading tool to circumferentially traverse the internal surface of the tube and displace the metal thereof outwardly into the circumferential channel of said die members to thereby form in the tube a circumferential bead conforming to the cross-sectional size and configuration of the said channel and tool element.

9. A tube beading tool comprising a tubular body member having an annular flange interiorly thereof intermediate its ends, complementary die members removably positioned inwardly of one

end of said body member in abutting relation with said flange and cooperating to define a socket therein disposed coaxially with respect to said body member to receive the end portion of a tube to be beaded, said die members each having a groove of arcuate cross-section shape in its inner surface cooperable to form a continuous circumferential channel in the wall of the socket defined thereby, an actuating member having a portion thereof mounted within the other end of the tubular body member in oppositely abutting relation with respect to the internal flange thereof and arranged for rotation coaxially with respect to said body member and the tube receiving socket defined by said die members, a recess extending axially inward from the inner end face of said actuating member, a spindle having one end thereof pivotally mounted within said recess for movement about an axis normal to the rotational axis of said actuating member and having its free end projecting endwise outwardly of the recess into the tube receiving socket of said die members, a beading tool element rotatably carried by the free end of said spindle for rolling engagement circumferentially about the inner wall surface of a tube positioned in said socket in registry with the continuous channel thereof, means carried by said actuating member adjacent its inner end and adjustable radially thereof to angularly position the

spindle and engage the beading tool element outwardly against the internal wall surface of a tube positioned in said socket, and means to rotate said actuating member relative to the body member 5 and cause the beading tool elements to circumferentially traverse the internal surface of the tube and displace the metal thereof outwardly into the circumferential channel in said die members to thereby form in the tube a circumferential bead conforming to the cross-sectional size and configuration of the said channel and tool element.
